(57) **CLAIM**

The ornamental design for a sticker, as shown and described.

DESCRIPTION

FIG. 1 is a plan view of a sticker in accordance with a preferred embodiment of the present invention; FIG. 2 is a bottom end view of the sticker of FIG. 1; FIG. 3 is an top end view of the sticker of FIG. 1; FIG. 4 is a left side view of the sticker of FIG. 1; FIG. 5 is a right side view of the sticker of FIG. 1; and, FIG. 6 is a top plan view of a sticker in accordance with an alternate preferred embodiment of the present invention. The design is for a sticker and contains two embodiments. The first embodiment is shown in FIGS. 1 through 5. The second embodiment is shown in FIG. 6. The second embodiment is a mirror image of the first embodiment. The top view (FIG. 1) of the first embodiment is also the bottom view of the second embodiment. The left side view of the first embodiment (FIG. 4) is also the right side view of the second embodiment. Similarly, the right side view (FIG. 5) of the first embodiment is also the left side view of the second embodiment.
